UNITED STATES PATENT OFFICE.

PAUL MEURISSE, OF LILLE, FRANCE.

STEAM-BOILER.

No. 811,785.

Specification of Letters Patent.

Patented Feb. 6, 1906.

Application filed July 18, 1905. Serial No. 270,215.

To all whom it may concern:

Be it known that I, PAUL MEURISSE, a citizen of France, residing at 4 Rue des Meuniers, Lille, France, have invented new and useful 5 Improvements in Steam - Boilers, of which the following is a specification.

This invention relates to a steam-boiler occupying a very small space, considering its great evaporative power, and characterized 10 by its particular construction, which consists of an upper tubular transversal body; a cluster of fire-tubes arranged in this tubular body; a vertical layer of water and an almost horizontal layer of water, both connected with 15 the tubular body and making between them an angle of less than ninety degrees; a cluster or nest of vaporizing or water tubes joining the two layers of water; a grate formed by water-circulating tubes connecting the vertical layer of water to a transverse collector and by fire-bars interposed between these tubes, and a group of vertical tubes forming 20 a water-wall and connecting the transverse collector with the horizontal layer of water. 25 In the annexed drawings, Figure 1 is a vertical longitudinal section of the boiler. Fig. 2 is a front view of the furnace. Fig. 3 is a transverse section. Figs. 4 and 5 are sectional detail views, to enlarged scale, showing 30 the connection of the boiler-tubes. Fig. 6 is an elevation of a portion of a bar of the grate. Fig. 7 is a plan of this bar. Fig. 8 is a transverse section.

The boiler is composed of an upper transverse body or drum *a*, having two opposite flat portions *b c*, forming tube-plates, slightly inclined to the horizontal to prevent sediment from settling on the lower plate. In these plates are expanded fire-tubes *d*, arranged in quincunx form. This upper transverse body *a* forms a reservoir of water and steam and joins two headers *ef*, one, *e*, a vertical header leading from the lower part of the drum and serving to return the water, the 45 other, *f*, discharging almost on the horizontal axis of the body and serving to receive the steam. The axis of this latter header is slightly inclined to the horizontal and forms, with the axis of the vertical header, an angle 50 less than ninety degrees.

The headers are united by a nest or cluster of vaporizing-tubes composed of water-tubes *g*, having the form of the arc of a circle whose center is at the point of intersection of the 55 axes of the headers. The tubes *g* are arranged in quincunx form and are mounted in

such a manner as to be easily removable and accessible, as shown in Figs. 3 and 4. On the side of the vertical header these tubes have an opening made in the lower face of the tube 60 to insure the circulation of the water in the tubes, while preventing the deposit of sediment in the same. On the side of the other header the tubes *g* have holes throughout their circumference. 65

The vertical header is extended beneath the boiler, and from the foot is led a series of tubes *h*, connected with a transverse collector or box *i*. Two or more rows of vertical tubes *j*, arranged in quincunx form, connect 70 the collector *i* with the horizontal header, serving to collect the steam.

The tubes *h* are disposed at such a distance apart as to enable to be fitted therein fire-bars of special construction. (Shown more 75 clearly in Figs. 5, 6, and 7.) The combination of the tubes *h* with these bars forms the boiler-grate.

The feeding and removal of the water from the boiler takes place in the lowest zone of 80 the layer of return-water, in which the deposit of the sediment also takes place.

Continued circulation of the gases is insured by baffles *l m n*, the baffle *l* being constituted by gratings placed between the tubes 85 *g* of the lower row of the tubular nest. The steam-outlet is through the tube *o*, and the exit of the gases takes place through the chimney *p*.

The boiler is completed by a sheet-iron casing, in which is left in the lower part an opening *r* for charging the fuel. This casing is also provided with doors *s* for the inspection 90 of the tubes *g*.

The arrangement just indicated affords a 95 large combustion-chamber notwithstanding the small height of the apparatus. The gases rise from the grate, licking the lower part of the group of water-tubes, and also the vertical tubes *j*, forming a water-wall, descend again around the tubes *g* in order to pass finally through the fire-tubes *d* of the upper part *a* and issue to the chimney. There is thus a very long passage for the gases, 100 which is favorable to the economical utilization of the heat. This passage is indicated by arrows in the drawings.

The circulation of the water in the boiler is also indicated by arrows in the annexed drawings. This circulation, which is very 105 active, prevents the sediment from settling in the tubes *g*. This sediment settles in the

lower part of the vertical header *e*, from which it is easy to extract it. The scale, on the other hand, settles in the tubes *h* and *j*, which are the most heated and which can be 5 easily cleaned on account of their position and because they are straight.

The water in the water-tubes vaporizes by the transmission of heat, carrying with it a certain quantity of water, and this mixture, 10 discharging into the steam-collector, passes into the upper body, where the separation of the steam occurs. This steam, being besides obliged to lick the upper part of the smoke-tubes, is slightly superheated before leaving 15 the boiler by reason of the double course which it is obliged to make around the fire-tubes.

I claim—

1. A steam-boiler comprising an upper 20 transverse tubular body *a* situated in the path of the products of combustion in combination with a vertical header *e* communicating with the said tubular body, a header, substantially horizontal, communicating with 25 said tubular body, and a cluster of water-tubes *g* connecting the two headers, and substantially concentric with the tubular body *a*, substantially as described and for the purpose specified.
- 30 2. A steam-boiler comprising an upper transverse tubular body *a* situated in the path of the products of combustion and having two opposite flat portions *b*, *c*, forming tube-plates slightly inclined to the horizontal, in which are expanded fire-tubes *d*, in combination with a vertical header *e* communicating with the said tubular body, a substantially horizontal header *f* discharging into said tubular body, and a nest of water-tubes *g* connecting the two headers substantially concentric with the tubular body *a*, substantially as described and for the purpose specified.
- 35 3. A steam-boiler comprising an upper transverse tubular body *a* having two flat portions *b*, *c*, forming tube-plates slightly in-

clined to the horizontal, in which are expanded fire-tubes *d*, in combination with a vertical header *e* communicating with said tubular body; a header, substantially horizontal, 50 communicating with said tubular body; a nest of water-tubes *g* connecting the two headers, and substantially concentric with the tubular body; water-circulating tubes *h* connected at one end to the vertical layer of 55 water; a transverse collector *i*, into which the other ends of the tubes *h* discharge; said tubes *h* being situated in proximity to the grate; and a group of vertical tubes *j* forming a water-wall, and connecting the transverse collector *i* with the horizontal header, substantially as described and for the purpose specified.

4. A steam-boiler, comprising an upper transverse tubular body *a*, having two flat 65 portions, *b* and *c*, forming tube-plates, slightly inclined to the horizontal, into which are expanded fire-tubes *d* in combination with a vertical header *e* communicating with the said tubular body; a header *f*, substantially 70 horizontal, communicating with the said tubular body; a nest of water-tubes *g* traversing the two headers, and having their ends at the side of the vertical header slightly narrowed and perforated on the bottom side, while the 75 ends at the side of the other header are perforated throughout their circumference; tubes *h*, for the circulation of water, discharging at one end into the vertical header; a transverse collector *i*, into which the other ends of 80 the water-tubes *h* discharge; and a group of vertical tubes *j* forming a water-wall, and connecting the transverse collector *i* with the horizontal header *f*, substantially as described and for the purpose specified. 85

In testimony whereof I have signed my name to this specification in the presence of two subscribing witnesses.

PAUL MEURISSE.
